CLAIM

The ornamental design for a glove with palm stitching, as shown and described.

DESCRIPTION

FIG. 1 is a back perspective view of a glove with palm stitching, showing our new design;

FIG. 2 is a front perspective view thereof;

FIG. 3 is a back elevation view thereof;

FIG. 4 is a front elevation view thereof;

FIG. 5 is a right side elevation view thereof;

FIG. 6 is a left side elevation view thereof;

FIG. 7 is a top plan view thereof; and,

FIG. 8 is a bottom view thereof.

While a right-handed glove is shown and claimed, the right-handed glove is typically sold with a left-handed glove having a design that is a mirror image of the right-handed glove.

The dash-dot-dash lines shown in the figures illustrate portions of the glove with palm stitching that form no part of the claimed design.

The broken lines shown in the figures represent stitching and form part of the claimed design.
